UNITED STATES PATENT OFFICE

SAMUEL A. WILDE, OF TAUNTON, MASSACHUSETTS, ASSIGNOR TO GLENWOOD RANGE COMPANY, OF TAUNTON, MASSACHUSETTS, A CORPORATION OF MASSACHUSETTS

DROP DOOR

Application filed September 6, 1929. Serial No. 390,728.

The invention relates to an improvement in drop doors of the type which are pivotally supported and spring-controlled and which are especially adapted for stoves, although they may be used in other connections where a drop door is wanted.

In present day practice, both in stoves and in other structures where a drop door is used, it is desirable that the front of the door or structure in which the door is located shall present an appearance undefaced by any of the parts used for controlling the door. In other words, all of these parts should be concealed in so far as possible. About all of the present day stoves or structures where a drop door is used are either enamelled or provided with some finish which if marred would disfigure the stove or structure. It is accordingly necessary that all parts entering into the operation of the door, and the operation of the door itself, shall be such as to avoid all possibility of marring the finished surface of the stove or structure.

The essential objects of my invention are accordingly to provide a pivoted drop door, spring-controlled, in which all parts entering into the support and control of the door are concealed, and which parts are also of such character as will not mar or permit the door during its operation to mar the exterior or finished surface of the stove or structure within which the door is arranged.

Among the further objects of my invention are: to provide such pivotal support and retention for the door as will permit of the door being easily mounted and all parts assisting in its control easily applied; to provide a tight door when closed, and to provide stops for the door when open, which stops are so arranged that no enamelled or finished surface of the door will engage said stops.

The invention can best be seen and understood by reference to the drawings, in which—

Fig. 1 is a front elevation of the door and its surrounding casing.

Fig. 2 is a rear inside elevation of the door and its surrounding casing, showing also various parts entering into the control of the door.

Fig. 3 is a section on the line 3—3 of Fig. 1. Fig. 4 is a section on the line 4—4 of Fig. 1. Fig. 5 is a section on the line 5—5 of Fig. 1. Fig. 6 is a section substantially the same as Fig. 5, excepting that the door is in an open position with certain of the operating parts occupying a changed position from that shown in Fig. 5.

Fig. 7 is a section on the line 7—7 of Fig. 2, and

Fig. 8 is an inside rear elevation of a portion of the door and casing adjacent one of the door trunnions showing a modified stop arrangement to which special attention will later be directed.

1 represents the door, 2 its handle. The door is framed by a casing forming a part of the stove body or structure within which the door is arranged. The casing comprises a top plate 3, side plates 4, 4, and a bottom plate 5. The exterior faces of these plates preferably lie substantially flush with one another. The side plates 4, 4 are each formed to provide a channel 6 running lengthwise or vertically along its interior side. This channel is formed by and between spaced inwardly projecting flanges 7 and 8, respectively, with which each side plate is provided. Of these flanges the flanges 7 form the jambs along the sides of the doorway within which the door is contained, and extending laterally from these jambs are turned edgings 9 against which the door closes. Supplementing the jamb edgings 9, 9 along the sides of the doorway is an edging 10 extending from the top plate 3 of the casing and against which the top of the door closes. In other words, the door along its top and sides closes against these edgings 9, 9, and 10, respectively. There is no edging against which the door closes at its bottom.

The door is provided with trunnions 11, 11. These trunnions extend outwardly from the opposite sides of the door at points adjacent its bottom edge but appreciably removed therefrom. The jambs 7, 7 which frame the sides of the doorway, and the turned edgings 9, 9 from these jambs, are cut away to receive the respective trunnions, sockets 12 being thereby formed in the re-

- spective jambs for the two trunnions. These sockets into which the trunnions project, and within which the trunnions are adapted to turn, are closed on all sides excepting on their interior or rear sides where the sockets are left open. The relative disposition of the trunnions on the door is, also, preferably such that when the trunnions are properly contained within their respective sockets they will extend outwardly into the channels 6, 6 of the side plates of the casing, with bearing against the bottoms of these channels which bearing assists in the retention of the trunnions.
- 15 It was explained above that both the jambs 7, 7 and the edgings 9, 9, inturned therefrom, are cut away to receive the respective trunnions. In fact, the edgings 9, 9 are cut away below the sockets for the trunnions, down to a point substantially flush with the top edge of the bottom plate 5 of the casing, and in an amount substantially equal to the thickness of the door, for it is by passing the door through the openings 13 thus provided by the cut away portions of the edging 9, 9, that the door may be hung upon the casing with the trunnions fitting in their respective sockets. The hanging of the door is effected as follows: It will be assumed that the handle 2 of the door has been removed. The door is then passed through the doorway so as to lie on the interior side thereof. The door is then turned into a horizontal position with the bottom side up and the top edge of the door, or the edge then facing the interior of the casing, is passed through the opening 13 provided by the cut away portions in jamb edgings 9, 9, until the trunnions draw into their respective sockets.
- 40 With the trunnions on the door thus socketed the door will become pivotally mounted, assuming that some means is provided for preventing the trunnions moving out of the open, rear sides of their respective sockets which are left open to permit of the trunnions being moved into the sockets when the door is applied or hung as just explained. The displacement of the trunnions through the open inner sides of their sockets would occur only when the door was opened. When the door is in a closed position bearing against the edgings projecting from the jambs and top plate of the casing, the trunnions will be held in place within their respective sockets, but when the door is opened, unless the trunnions are restrained they will move out through the open, rear sides of their sockets, and to prevent this the following means is provided.
- 55 In the first place it will be observed that when the door is opened that portion of the door lying above its trunnions will move outwardly and downwardly, while that portion of the door lying below its trunnions will move inwardly and upwardly. Fastened to

the bottom plate 5 of the casing on the interior side thereof and extending lengthwise this plate is a guard 15. This guard lies inwardly removed just forward of that portion of the door lying below its trunnions and which turns inwardly and upwardly as the door is opened, assuming that its trunnions are properly contained to turn within their respective sockets. The guard is provided on its outer side, or that side facing the bottom of the doorway, with a curved surface 16, which surface has substantially the same curvature as that of the arc described by the bottom edge of the door when the door is opened, and the arrangement of the guard is also such that the bottom edge of the door, as the door is opened, will preferably have bearing against the curved surface 16 of the guard during the opening of the door. Thus the guard, providing as it does a bearing for the bottom edge of the door, will operate to hold the trunnions within their respective sockets during the opening of the door. The guard 15 is preferably fastened to the bottom plate 5 of the casing in manner not to deface the outside surface of the plate. To this end the bottom plate is provided on its interior side with raised protuberances or bosses 17 which are internally threaded. The guard is provided with ears 18 having openings in them by which the ears will fit over the respective bosses. Fastening into the bosses are screws 19 and between the heads of these screws and the ears on the guard are washers 20 which on the tightening of the screws will bind against the ears, thereby securely fastening the guard to the bottom plate.

With the parts thus far provided the door might well function as a drop door for certain purposes, but no means has yet been provided for making the door spring controlled, and the only stop for the door when opened would be that presented by the top edge of the bottom plate 5, the door turning when open to a point where its face will have bearing against this edge which is a thing to be avoided as the face of the door will soon become disfigured.

Reference will now be made to the way in which the door is made spring controlled, and to the way in which stops are provided for holding the door in open position and which are so arranged that no enamelled or finished part of the door will engage the stops.

First in relation to the spring control: The end portions of the respective trunnions, or those portions which lie within the inside channels 6, 6 on the side plates 4, 4, bear cams 22. These cams when the door is closed occupy a downturned position substantially as shown in Fig. 7, and when the door is full open will turn by the turning of the trunnions to occupy a position substantially as shown in Fig. 6. Arranged to have en-

gagement with these cams on the trunnions are spring arms 23. These arms are arranged to lie within the inside channels 6, 6 on the side plates, the arms being fastened to the side plates at points well above the cams 22 and trunnions to which the cams are secured. From the points of their fastening the arms extend downward to embrace and have bearing against the cams, the cams, in other words, having bearing engagement with the interior surface 24 on the bottom end portions of the respective spring arms. To avoid defacing the outside surfaces of the side plates the spring arms are preferably fastened to them in the same manner that the guard 15 is fastened to the bottom plate 5 of the casing, to which end the side plates on the inside are provided with raised protuberances or bosses 25 internally threaded. The upper ends of the spring arms are arranged to bear against the bottom of the channels within which the arms are contained, and are provided with openings in them fitting over the respective bosses. Screws 26 fasten into the respective bosses and washers 27 are interposed to lie between the heads of the screws and the arms, and on the tightening of the screws the washers will bind against the arms thereby securely fastening them to the side walls of the casing. The relation of the spring arms to the respective cams on the trunnions, while the door is occupying a closed position, is preferably such that the arms will be slightly distorted so that the tension of the arms, operating through the respective cams and trunnions, will operate to hold the door in a closed position. The relation of the cams to the surfaces on the spring arms against which they have bearing is, also, preferably such that the spring arms will not become greatly distorted so as to impart any considerable tensional resistance until the door has been brought to about a full open position and the cams moved to approach a position substantially as shown in Fig. 6. At such times the cams will operate to rather forcibly distort the spring arms which accordingly will operate to bring the door when open to an easy stop.

Apart from the function of spring control effected by the spring arms as just described, these arms perform another useful function by their bearing against the cams on the respective trunnions, namely,—they operate to hold the trunnions in their respective sockets so that the trunnions cannot move out of the open inner sides of their sockets as the door is opened. As previously explained, the guard 15 performs a similar function, but with the spring arms thus preventing displacement of the trunnions the use of the guard for such purpose is no longer necessary and, accordingly, when the spring arms are employed the preferred arrangement is such

that the guard 15 will be so arranged that the bottom edge of the door will not have contact with it as the door is opened. The guard is retained however for the purpose of retaining the trunnions in case anything should happen to the spring arms. 70

For maintaining the door in its full open position but out of contact with the top surface of the bottom plate 5 of the casing, with which the door when full open might otherwise have bearing, stops 30 are provided on the insides of the spring arms with which the cams on the trunnions have engagement when the door has been moved to a full open position. The stops thus provided are augmented by another set of stops for holding the door when in full open position. As was before explained, when the door is opened that portion of the door lying below its trunnions will turn inwardly and upwardly. 80 Projecting laterally from the lower ends of the respective spring arms are offsets 31, and located on these offsets are stops 32 which lie within the path described by that portion of the door lying below its trunnions, the arrangement being such that the inner face of said portion of the door will be brought into engagement with these stops 32 on the arm offsets when the door has been turned to a full open position. The two sets of stops 90 thus provided not only relieve one another of the strain that would come upon any one set, but reduce to a minimum the danger of the outer face of the door ever contacting with the top surface of the bottom plate of the casing, which would happen in case that all of the inside stops were eliminated, a danger that could hardly occur. 100

In the hanging of the door and the assembling of its various parts the door is first hung with its trunnions socketed in the jambs of the casing, as explained above, before the handle of the door has been applied to it and before the application of the guard 15 to the bottom plate of the casing. Afterwards these parts are fastened in their proper places together with the spring arms. 110

Instead of placing the offsets 31 which bear the stops 32 on the ends of the spring arms, these stop bearing offsets may be placed on the opposite ends of the guard 15 as shown in Fig. 8, and this by simply extending the ends of the guard. 115

Having thus fully described my invention, I claim and desire to secure by Letters Patent of the United States:

1. In a drop door assembly which includes a casing having a doorway in it, and a door having trunnions pivotally arranged to turn upon the jambs of the casing, said trunnions extending from the opposite sides of the door above the bottom edge thereof whereby that portion of the door lying below its trunnions will swing inwardly and upwardly as the door is outwardly opened, said jambs of the 120

casing being provided with sockets for receiving said trunnions, which sockets are open on the interior sides thereof whereby the trunnions may be inserted into said sockets 5 from the interior side of the casing on passing the door outwardly through the doorway from the interior side of the casing, and means for preventing withdrawal of the trunnions from their respective sockets during 10 the opening and closure of the door comprising a guard on the interior side of the casing forward of that bottom portion of the door lying below its trunnions when the door is in a closed position, said guard being arranged 15 whereby said bottom portion of the door, lying below its trunnions as aforesaid, will engage the guard during the opening and closure of the door before the trunnions on the door have moved out of their respective sockets.

2. In a drop door assembly which includes a casing having a doorway in it, and a door having trunnions pivotally arranged to turn upon the jambs of the casing, cams borne 25 by said trunnions, spring arms fastened to the side walls of the casing and located on the interior thereof with extension to have engagement with said cams, and stops borne by said arms and arranged in the paths of 30 said cams to be engaged thereby when the door is opened.

3. In a drop door assembly which includes a casing having a doorway in it, and a door having trunnions pivotally arranged to turn 35 upon the jambs of the casing, said trunnions extending from the opposite sides of the door above the bottom edge thereof whereby that portion of the door lying below its trunnions will swing inwardly and upwardly as 40 the door is outwardly opened, cams borne by said trunnions, spring arms fastened to the side walls of the casing and located on the interior thereof with extension to have engagement with said cams, and stops arranged in 45 the path of said portion of the door lying below its trunnions to be engaged thereby when the door is opened.

4. In a drop door assembly which includes a casing having a doorway in it, and a door 50 having trunnions pivotally arranged to turn upon the jambs of the casing, said trunnions extending from the opposite sides of the door above the bottom edge thereof whereby that portion of the door lying below its trunnions 55 will swing inwardly and upwardly as the door is outwardly opened, said jambs of the casing being provided with sockets for receiving said trunnions, which sockets are open on the interior sides thereof whereby 60 the trunnions may be inserted into said sockets from the interior side of the casing on passing the door outwardly through the doorway from the interior side of the casing, a guard fixed to said casing on the interior side 65 thereof and presenting a surface lying just

forward of the plane traversed by the bottom edge of the door when the door is opened, cams borne by said trunnions, spring arms fastened to the side walls of the casing and located on the interior thereof with extension to have engagement with said cams, stops borne by said arms and arranged in the paths of said cams to be engaged thereby when the door is opened, and stops arranged in the path of said portion of the door lying below its trunnions to be engaged thereby when the door is opened.

5. In a drop door assembly which includes a casing having a doorway in it, and a door having trunnions pivotally arranged to turn upon the jambs of the casing, said trunnions extending from the opposite sides of the door above the bottom edge thereof whereby that portion of the door lying below its trunnions will swing inwardly and upwardly as the door is outwardly opened, said jambs of the casing being provided with sockets for receiving said trunnions, which sockets are open on the interior sides thereof whereby the trunnions may be inserted into said sockets from the interior side of the casing on passing the door outwardly through the doorway from the interior side of the casing, means for preventing withdrawal of the trunnions from their respective sockets during the opening and closure of the door comprising a guard on the interior side of the casing forward of that bottom portion of the door lying below its trunnions when the door is in a closed position, said guard being arranged whereby said bottom portion of the door, lying below its trunnions as aforesaid, will engage the guard during the opening and closure of the door before the trunnions on the door have moved out of their respective sockets, and means for tensionally holding the trunnions in their respective sockets and for frictionally impeding the opening of the door.

6. In a drop door assembly which includes a casing having a doorway in it, and a door having trunnions pivotally arranged to turn upon the jambs of the casing, said trunnions extending from the opposite sides of the door above the bottom edge thereof whereby that portion of the door lying below its trunnions will swing inwardly and upwardly as the door is outwardly opened, said jambs of the casing being provided with sockets for receiving said trunnions, which sockets are open on the interior sides thereof whereby the trunnions may be inserted into said sockets from the interior side of the casing on passing the door outwardly through the doorway from the interior side of the casing, means for preventing withdrawal of the trunnions from their respective sockets during the opening and closure of the door comprising a guard on the interior side of the casing forward of that bottom portion of the door lying below its trunnions when the door is in a closed position, said guard being arranged whereby said bottom portion of the door, lying below its trunnions as aforesaid, will engage the guard during the opening and closure of the door before the trunnions on the door have moved out of their respective sockets, and means for tensionally holding the trunnions in their respective sockets and for frictionally impeding the opening of the door.

the door lying below its trunnions when the door is in a closed position, said guard being arranged whereby said bottom portion of the door, lying below its trunnions as afore-
5 said will engage the guard during the opening and closure of the door before the trunnions on the door have moved out of their respective sockets, means for tensionally holding the trunnions in their respective sockets
10 and for frictionally impeding the opening of the door, and a stop on said guard arranged in the path of said portion of the door lying below its trunnions to be engaged thereby when the door is opened.
